WINDSHIELD CLEANING BLADE

Anton Rappi, Eggertsville, N. Y., assignor to Trico Products Corporation, Buffalo, N. Y.

Application September 19, 1947, Serial No. 774,906

6 Claims. (Cl. 15—250)

1

This invention relates to the windshield cleaning art and more particularly to the wiper blade, the same being an improvement on the disclosure made in copending application Serial No. 655,637, now Patent No. 2,618,806, November 25, 1952, wherein is shown and claimed a blade mounting in which an arm engaging clip or housing is pivotally mounted on the back of the blade and provided with a chamber for enclosing a latch spring which secures the connection between the blade and its actuating arm.

The primary object of the present invention is to simplify the blade mounting and thereby render it more economical in production.

A further important object of the invention resides in an improved construction which will facilitate the assembly of the clip parts and at the same time provide an improved action tending to normalize the blade with respect to the surface being wiped.

The foregoing and other objects will manifest themselves as the following description progresses, reference being had to the accompanying drawing, wherein:

Fig. 1 is a fragmentary side elevation depicting a windshield cleaner constructed in accordance with the present invention;

Fig. 2 is an enlarged longitudinal section through the blade mounting; and

Fig. 3 is a transverse sectional view about on line 3—3 of Fig. 2.

Referring more particularly to the drawing, the numeral 1 designates a power shaft on the outer end of which is fixed a wiper arm having a mounting section 2 and a blade carrying section 3 pivotally joined by pin 4 and normally urged toward the windshield glass 5 by a flat spring 6 bearing upon a shoulder 7 on the mounting section. The outer end of the arm is formed with a curved tongue 8 having a latch shoulder 9 designed for engaging with a shoulder 10 on the mounting clip or housing 11, such engagement being detachably maintained by a flat spring 12 so as to operatively secure the blade to its actuating arm.

In the earlier disclosure the housing was die cast, whereas in the present disclosure the clip housing is the product of a die stamping operation. The blank from which the housing is stamped has lateral wings downturned to provide side walls 13 and also has longitudinally extending ears which are downturned to form the end walls 14, such ears and wings projecting from the margins of an intermediate body portion which constitutes the back wall 15 of the housing. The back wall is formed with an opening 16 and an

2

adjacent depression which latter forms an internal convex wall 17 designed to more or less nestingly fit within a curved tongue 8 of the wiper arm. The wall 17 is relieved at 18 to provide the shoulder 10 and also to receive the interlocking latch shoulder 9 under the urge of the spring 12. The opposite ends of the spring are formed with projections 19 which engage in openings 20 in the opposite end walls 14, thereby locating the spring in its proper position and supporting the same with an upward bow or convexity in contact with the convex wall 17 of the housing. When inserting the arm tongue 8 through the opening 16, the intermediate portion of the spring is depressed so as to permit the shoulder 9 passing beyond the shoulder 10 whereupon the spring will lift the arm terminal and hold the shoulders cooperatively engaged.

The clip housing 11 is pivotally mounted on the blade for permitting the latter to rock about its wiping edge and assume an inclined dragging position at the beginning of each stroke. To this end the opposite end walls 14 are formed with bearings 21 to freely receive the blade carried pintles 22. For limiting the rocking movement of the blade on its mounting 11, lateral stops 23 are provided on the blade beneath the lower edges of the side walls 13 so as to be contacted by the same and thereby determine the wiping position of the blade, as indicated by the broken lines 24. These ears 23 and the pintles 22 may be struck from the sheet metal backing or channeled member 25 of the blade which is of channel form and which clampingly embraces the rubber or squeegee body 26. Or, a separate channeled member 27 may be provided especially for this purpose, as shown. The channeled member 27 is inverted over the back of the channeled holder 25 to straddle the same, in which position it is firmly secured by a rivet 28. The pintles are struck upwardly to elevate them slightly from the back wall 29 and are also given a channeled form for reinforcement. The stop ears 23 are stamped from the side walls of the blade carried clip section 27 and preferably lie in the plane of the back wall 29 so as to give increased breadth thereto for insuring position-determining engagement with the lower margins of the side walls 13.

A normalizing spring 30 bears upon the back wall 29 and exerts upward pressure on the mounting clip 11 in a manner normally to urge the blade to an upright position on the surface being wiped. This normalizing spring 30 is illustrated in the form of a bowed flat spring having its intermediate convex portion squarely seating

upon the flat back wall 29 with its square ends exerting upward pressure against the under side of the flat latch spring 12 at points adjacent the end walls 14.

By slightly springing one end wall 14 the pintles 22 may be engaged in their bearings 21 after the preliminary positioning of the oppositely bowed springs 12 and 30. Therefore, the parts within the clip housing may readily be assembled. The intermediate portion of the normalizing spring has oppositely extending lateral parts 31 which underlie the lower edges of the side walls 13 and thereby serve to properly support the spring in place. The several parts of the mounting clip, with or without its blade straddling section 27, are readily stamped from sheet metal stock. The side walls 13 may be cut away to conform to the shape of the depressed wall 17 for enhancing the appearance.

While the foregoing description has been given in detail, it is apparent that the inventive concept and teaching of the present disclosure are capable of assuming other physical embodiments without departing from the spirit of the invention and the scope of the appended claims.

What is claimed is:

1. A wiper blade member, an arm attaching clip member extending lengthwise thereof, means pivotally connecting the two members to permit the blade rocking laterally upon its wiping edge, the clip member being in the form of a hollow housing having a back wall and end walls which oppose each other, the latter being relatively displaceable and formed with seats, and a flat spring having its opposite ends engaged in the seats under compression to support the spring bowed toward the back wall and removable from the end walls upon their relative displacement, the back wall having an opening for interlockingly receiving one end of an actuating arm against the action of said spring.

2. A wiper blade member, an arm attaching clip member, means pivotally connecting the two members, the clip member being in the form of a hollow housing having a back wall opposite the blade member and also opposed end walls, the latter being formed with seats, a flat spring having its opposite ends engaged in the seats to support the spring under compression bowed toward the back wall, the back wall having an opening for interlockingly receiving one end of an actuating arm against the action of said spring, and a second bowed flat spring having its opposite ends bearing upon the first spring and its intermediate portion reacting against the blade member for exerting a normalizing influence on the wiper blade with respect to the surface being wiped.

3. A wiper blade having an inverted channelled member with a flat back and oppositely extending stop parts struck outwardly from the opposite sides thereof of the channel to extend in the plane of the back, an arm attaching clip housing pivotally connected to the channelled member for lateral swinging about a fixed longitudinal axis and having depending side walls engageable with the stop parts to determine the dragging inclination of the blade with respect to

the clip housing when in operation, and a spring contained within the housing and exerting a downward normalizing pressure on the back wall at opposite sides of the longitudinal axis tending to urge the blade to an upright position on the surface being wiped.

4. A wiper blade, an arm attaching clip housing pivotally connected thereto and having an arm receiving recess in its back for receiving a latch part of the arm, a spring in the housing opposing the back wall and yieldable therefrom to permit insertion of the latch part in the recess and thereafter to hold the latch part operatively associated with the recess of the clip, and a second spring having bearing support on the first spring and reacting on the blade for exerting a normalizing urge thereupon.

5. A wiper blade, an arm attaching clip housing pivotally connected thereto and having a chamber opening toward the blade with a recess in its back for receiving a latch part of the arm, a spring in the housing extending lengthwise of the blade and acting toward the back of the chamber to hold the latch part engaged with a shoulder on the clip housing, the back of the blade having a transverse bearing surface, and a second spring compressed between the first spring and the bearing surface for exerting a normalizing urge upon the blade, both springs being insertable into the chamber through the open side thereof and preliminary to pivotally mounting the clip upon the blade whereby the blade will serve to hold the springs against displacement from the chamber.

6. A wiper blade having oppositely extending pintles, an arm attaching clip housing in the form of an inverted cupped stamping having opposing side and opposing end walls depending from a back wall, the back wall of the housing having an arm receiving opening for receiving an interlockable arm terminal, the opposing end walls having spring seats and pintle bearings, a flat spring within the housing having its opposite ends engaged in the seats and being wholly supported by the housing in opposition to the back wall for yieldably holding the arm terminal engaged therewith, said clip housing and spring being mountable on the blade as a unit, and said end walls being relatively displaceable to engage the pintles in the bearings and the spring in the seats, and means connecting the housing to the blade.
